UNITED STATES PATENT OFFICE

CORNELIS F. M. VAN BERKEL, OF WASSENAAR, NETHERLANDS, ASSIGNOR TO U. S. SLICING MACHINE COMPANY, OF LA PORTE, INDIANA, A CORPORATION OF INDIANA

SLICING MACHINE

Application filed June 16, 1928, Serial No. 285,900, and in the Netherlands June 30, 1927.

This invention relates to slicing machines having a power driven rotating knife and a work table that is manually reciprocated past the edge of the knife.

It is the object of this invention to provide the work table with a feeding mechanism that will be actuated by the operator when he reciprocates the work table.

One embodiment of the invention is illustrated in the accompanying drawings.

Fig. 1 is a side elevation of a meat slicing machine according to the invention;

Fig. 2 is a top plan view; and

Fig. 3 is a detail on a larger scale.

In these figures, 1 indicates the frame of the machine, 2 the bracket in which the knife 3 is rotatably mounted, 4 the reciprocating carriage, and 5 the upper table which is movable transversely thereon. 26 is an electric

motor for rotating the slicing knife 3.

The feeding mechanism for the work table 5 comprises a screw 6 journaled in lugs 15 and 16 extending from the carriage and a half-nut 8 carried by the work table 5 through 25 the arms 24 and 22. These arms are pivoted at 23 and a spring 25 urges the half-nut 8 against the screw 6. A sleeve 9 surrounds the screw 6 and is fixed at one end in the lug 15 and the other end rests on the smooth 30 portion of the screw 6. A handle 10 is journaled on the sleeve 9 through bearing portions 17 and 18. The handle 10 carries stop lugs 11 and 12 located on opposite sides of the sleeve 9 which co-operate with stop lugs

35 13 and 14 carried by the carriage 4. The screw 6 has a ratchet 20 fixed to the one end which co-operates with a pawl 19 mounted on the handle 10. The size of the rotary steps of the ratchet wheel induced by the pawl 40 may be adjusted by means of an adjustable cap 21.

Fig. 3 shows on a larger scale how the sleeve 9 is provided with a slot on the lower 45 surface for permitting the entry of the segmental nut 8.

It will be seen that when the operator grasps the handle 10 to reciprocate the work carriage, the handle 10 will rotate about the 50 sleeve 9 until the lugs 11 abut the stop

lugs 13, whereupon the carriage 4 will be moved past the knife.

This initial rotary movement of the handle 10 will rotate the ratchet an amount determined by the distance between the lugs 11 55 and 13. At the end of the reciprocating movement of the carriage, the operator pulls on the handle 10 and rotates it in the opposite direction until the lugs 12 abut the stop lugs 14 whereupon the carriage 4 will be pulled 60 toward the operator. The rotation of the handle 10 on this reverse movement of the carriage 4 will reset the pawl on the ratchet, as shown in Fig. 1.

The cap 21 is held in adjusted position by 65 the engagement of one end of the spring 27 supported at 28 on the carriage 4, with a selected one of the openings 26 in the cap 21.

I claim:

1. In a slicing machine having a power 70 rotated slicing knife, a carriage mounted to be reciprocated past the edge of said knife, a work table on said carriage, a handle for manually reciprocating said table, said handle being movable relative to said table when force is applied to reciprocate said table, a feeding mechanism mounted on the same side of said table as said handle, and a connection between said feeding mechanism and handle 75 causing the actuation of said feeding mechanism during the movement of said handle in one direction.

2. In a slicing machine having a slicing knife, a carriage mounted to reciprocate past the edge of said knife, a work table on said carriage, a handle to manually reciprocate said table, said handle being movable relative to said table when force is applied to reciprocate said table, said handle being movable toward said knife when pushed to move said table past the edge of said knife on the cutting stroke and being movable in the opposite direction when it is pulled to move said table in the opposite direction, and feeding mechanism mounted on the same side of said table as said handle, said feeding mechanism being actuated when said handle moves in one direction but inoperative when said handle moves in the other direction.

3. In a slicing machine having a slicing 100

knife, a carriage mounted to reciprocate past the edge of said knife, a work table on said carriage, a handle to manually reciprocate said table, said handle being movable relative to said table when force is applied to reciprocate said table, said handle being movable toward said knife when pushed to move said table past the edge of said knife on the cutting stroke and being movable in the opposite direction when it is pulled to move said table in the opposite direction, feeding mechanism, said feeding mechanism being actuated when said handle moves in one direction but inoperative when said handle moves in the other direction, said feeding mechanism comprising a feed screw journaled on said carriage and connected with said table through a travelling nut meshing with said screw, a ratchet on said screw, and a pawl on said handle.

4. In a slicing machine having a rotatably mounted slicing knife and a carriage mounted for reciprocation past the cutting edge of said knife, a work table on said carriage, a feeding mechanism for said work table, a handle for manually reciprocating said carriage, said handle being movable relatively to said carriage, means for limiting said movement of said handle in either direction, said means imparting movement to said table upon the continued application of force to said handle after said handle has moved relative to said table the amount permitted by said means, and means on said handle to actuate said feeding mechanism during the relative movement of said handle with respect to said table.

5. In a slicing machine having a slicing knife, a carriage mounted to reciprocate past the edge of said knife, a work table on said carriage, a pivotally mounted handle carried by said carriage, the arc of rotation of said handle in either direction being limited by contacting portions on said carriage and handle, said handle being effective to move said carriage past the cutting edge of said knife after said handle has rotated through the arc permitted by said contacting portions, feeding mechanism mounted adjacent the handle for said work table, and a connection between said handle and feeding mechanism to actuate said feeding mechanism when said handle is rotated in one direction, said connection being inoperative to actuate said feeding mechanism when said handle is rotated in the opposite direction.

6. In a slicing machine having a slicing knife, a carriage mounted to reciprocate past the edge of said knife, a work table on said carriage, a feed screw journaled in said carriage and meshing with a traveling nut on said work table, a ratchet on said feed screw, a handle pivoted co-axially with said feed screw, means for limiting the rotative movement of said handle in either direction, said

means imparting movement to said carriage upon the continued application of force to said handle, and a pawl on said handle to engage said ratchet when said handle is rotated in one direction.

7. In a slicing machine having a slicing knife and a reciprocating carriage, a work table on said carriage, a feed screw journaled in said carriage, a ratchet on said feed screw, a rigidly mounted slotted sleeve enclosing said screw, a traveling nut carried by said work table and meshing with said screw through the slot in said sleeve, a handle journaled on said sleeve for limited rotation, and a pawl on said handle to engage said ratchet.

8. A slicing machine comprising a movable carriage, a work table movable relatively to said carriage, a slicing knife past which the carriage is adapted to move, a handle mounted on said carriage for actuating said carriage, said handle being movable relative to said carriage, feeding mechanism mounted on said carriage adjacent said handle comprising a feed screw co-operating with a feed nut on said table, a ratchet on said feed screw, and a pawl on said handle adapted to actuate said ratchet when said handle is moved relative to said table.

9. A slicing machine comprising a work table, a slicing knife, a cross slide on said work table, a handle pivoted to said table, for moving said table past said knife, a feed screw on said table adjacent said handle, a feed nut on said cross slide, and a pawl and ratchet connection between said handle and said feed screw for causing said handle to operate said feed screw when said handle is moved relative to said table.

10. A slicing machine comprising a work table, a slicing knife, a cross slide on said work table, a handle pivoted to said table for moving said table past said knife, a feed screw on said table, a feed nut on said cross slide, a pawl and ratchet connection between said handle and said feed screw for causing said handle to operate said feed screw when said handle is moved about its pivot, and means for varying the amount of movement imparted to said feed screw by said pawl and ratchet connection.

11. A slicing machine comprising a work table, a slicing knife, a cross slide on said work table, a handle pivoted to said table for moving said table past said knife, a feed screw on said table, a feed nut on said cross slide, a pawl and ratchet connection between said handle and said feed screw for causing said handle to operate said feed screw when said handle is moved about its pivot, and a shield arranged over said feed screw to provide means for preventing the accumulation of foreign particles upon said feed screw.

12. A slicing machine comprising a slicing knife, a movable support, a work sup-

port mounted thereon and adapted to move relatively to said first mentioned support, a feed screw on one of said supports, a shield substantially enclosing said feed screw, a nut on the other of said supports, and a handle 5 for actuating said feed screw and for moving said first mentioned support relatively to the slicing machine knife, said handle being concentrically mounted with respect to the axis of rotation of said feed screw.

10 13. In a slicing machine, the combination with a slicing knife, of a work table movable relatively thereto, a work supporting carriage slidably mounted on said table, a feed screw on said table co-operating with a feed nut on said carriage for moving said carriage relative to said table, a handle pivoted about said feed screw, and a connection between said handle and said feed screw for 15 operating the latter when said handle is moved about its pivot.

14. In a slicing machine, the combination with a slicing knife, of a work support movably mounted with respect thereto, a cross 20 slide on said work support, a feeding mechanism including a feed screw and a feed nut operatively connected to said support and said cross slide respectively and to each other for moving said cross slide relative to 25 said support, a shield substantially enclosing said feed screw, a handle having a portion encircling said shield to provide means whereby said handle may be pivoted about said shield and said feed screw, and operative connections between said handle and said feed screw for actuating the latter.

15. In a slicing machine, the combination with a slicing knife, of a work support movably mounted with respect thereto, a cross 30 slide on said work support, a feeding mechanism including a feed screw and a feed nut operatively connected to said support and said cross slide respectively and to each other for moving said cross slide relative to 35 said support, a stationary shield substantially enclosing said feed screw, a handle having a portion encircling said shield to provide means whereby said handle may be pivoted about said shield and said feed screw, and operative connections between said handle and said feed screw for actuating the latter.

16. A slicing machine comprising a work 40 table and a cross slide on said work table movable relatively thereto, a feed screw on said table, a feed nut on said cross slide co-operating with said feed screw to move said cross slide when said feed screw is actuated, a shield encircling said feed screw and bearing 45 on a portion thereof, a handle bearing on said shield and movable about the axis of said feed screw, and means for operatively connecting said handle to said feed screw so that the latter is actuated when said handle 50 is moved about said feed screw.

17. A device as claimed in claim 16 in which means are provided for limiting the movement of the handle in either direction about said feed screw.

18. A device as claimed in claim 16 in 50 which means are provided for predetermining the amount of movement which will be imparted to said feed screw.

19. In a slicing machine, the combination with a slicing knife, of a work support movable relative thereto, a feed screw on said support, a cross slide on said support having a nut adapted to engage said feed screw, a shield substantially enclosing said feed screw and rigidly supported at one end in a bearing rigidly mounted on said support, the other end of said shield being supported on a portion of said feed screw, a handle carried by said shield, operative connections between said handle and said feed screw whereby the feed screw is actuated when said handle is moved about said feed screw, stops for limiting the movement of said handle, and a means for limiting the amount of movement imparted to said feed screw by said handle, 80 said handle being adapted to move said carriage past said slicing knife after it has actuated said feed screw to feed said cross slide relatively to said support.

In testimony whereof I have signed my name to this specification on this 31st day of May, A. D. 1928.

CORNELIS F. M. VAN BERKEL.
